Primary Examiner — Kendra Leslie Hamilton

(57) **CLAIM**

The ornamental design for a teether, as shown and described.

DESCRIPTION

1. Teether

FIG. 1.1 is a perspective view of a teether showing my new design;

FIG. 1.2 is a front view thereof;

FIG. 1.3 is a rear view thereof;

FIG. 1.4 is a left view thereof;

FIG. 1.5 is a right view thereof;

FIG. 1.6 is a top view thereof; and

FIG. 1.7 is a bottom view thereof;

The broken lines shown in the figures are for the purpose of illustrating portions of the teether, which form no parts of the claimed design.

1 Claim, 7 Drawing Sheets(56)
